CRADLE OPERATING CYLINDER

David Wertman and Frank Warlick,
Washington, D. C.

Application November 30, 1943, Serial No. 512,396

10 Claims. (Cl. 121—38)

(Granted under the act of March 3, 1883, as
amended April 30, 1928; 370 O. G. 757)

This invention relates to hydraulic means for operating the cradle at a gun emplacement for handling large size ammunition between the hoist and the breach of the gun. Normally the ammunition is hauled up vertically by hoisting means and is placed in the cradle in substantially upright position while the cradle is retracted. In order to turn the ammunition into a more or less horizontal position for feeding into the gun barrel, the cradle in which the ammunition is placed has to turn through about 90°, while the cradle is simultaneously extended by a spanning tray so as to deliver the ammunition horizontally up to the mouth of the gun barrel.

It is the function of the present invention to operate the cradle by turning it from retracted or upright position to extended or lowered position and vice versa with proper speeds and accelerations, so as to reduce shock due to inertia and gravity forces of the massive cradle structure itself as well as the heavy pieces of ammunition that it is loaded with during the feeding portions of its operation.

Fig. 1 shows the general assembly of the cradle operating cylinder applied to a cradle of the four-link type.

Figs. 2 and 3 are sectional views taken at 2—2 and 3—3 respectively of Fig. 1.

Fig. 4 is a cross sectional view taken at 4—4 of Fig. 1.

Fig. 5 is a cross sectional view taken at 5—5 of Fig. 4, and

Figs. 6 and 7 are diagrammatic views of the hydraulic system used in the control of the cradle operating cylinder, Fig. 6 showing the controls in the cradle extending position, while the other figure shows them in cradle retracting position.

Figs. 8 to 10 are sections taken at 8—8, 9—9, and 10—10 respectively in Fig. 1.

The particular type and design of cradle shown in Fig. 1 is adapted to move the spanning tray 2 in a definite path in a restricted space as the main portion of the cradle is turned on its trunnions 9 from one position to the other. This is done by means of a four-link leverage system, the portion of the stationary base structure 10 between pivots 9 and 7 forming the stationary link, and the members 1, 2 and 6 providing the three movable links extending between the pivots 9 and 4, 4 and 5 and 7 and 5 respectively. The extended position of the cradle is shown in full lines, the dot and dash lines indicating it in the retracted position.

The cradle operating cylinder 13 is hinged at

12 to the base support 11 by means of bearing portion 45 pivotally mounted on the pin 44. End plate 49 is fastened to the base support and holds the pin 44 in place in the base support. End portion 47 is mounted at one side of the base support 11 to form a bearing for one end 29 of the oscillatable fitting 55, the other end of which bears in the side of the base support. End portion 48 is mounted at the side of plate 49 to perform a similar function for the oscillatable fitting 30, whose other bearing is formed in the plate 49.

These fittings provide the hydraulic connections between the passages in the base support 11 and the conduits leading to the cylinder valves.

The operating piston 43 in the cylinder chamber 31 has a rod 14 extending through the other end of the cylinder for pivotal connection at 46 to the main portion of the cradle at 8. The cradle

20 is shown in its extended position in Fig. 1 in full lines, and its retracted position is indicated by dot and dash lines. The hydraulic system for the operating cylinder is shown diagrammatically in Figs. 6 and 7. A hydraulic pump 33 is op-

erated by motor 32 and is supplied by fluid from the tank 34 through conduit 35. This pump de-

25 liveres the fluid under pressure through conduit 36 to the control valve 56 which is operated by control lever 40 to direct the pressure fluid into

30 either of the conduits 27 or 28 while at the same time relieving the other of these conduits to the return conduit 38 which leads back to the tank 34. A pressure relief valve 37 is used between the delivery conduit 36 and return conduit 38.

35 Conduits 27 and 28 are connected to the rigid base support as shown in Fig. 3. These conduits are connected through the oscillatable fittings 55 and 30 to the conduits 15 and 16 respectively,

which are rigid with the cylinder structure. Con-

40 duit 15 leads to the head end of the cylinder and supplies the fluid through check valve 20 and the adjustable orifice at 19 to the head end of the chamber 31 until the piston 43 clears the port 57. Then the fluid is supplied without re-

45 striction to chamber 31 until the control lever 40 is released or until the piston reaches the other end of the chamber. When lever 40 is re-

50 leased, spring 42 moves the control valve into neutral position, in which it permits the flow of fluid directly from the pump delivery conduit to the return conduit 38. While the piston is moving away from the head end of the cylinder the fluid at the other end is released through

55 the check valve 24 and the restriction at 23 to

the return conduit 38 via the conduits 16 and 28 and the control valve passages.

When the control lever 40 is shifted to the position shown in Fig. 7, the fluid under pressure is directed to the conduit 28, through conduit 16 and check valve 25 and the restriction at 26 to the rear end of the cylinder chamber until the port 58 is cleared by the piston and then the fluid under pressure flows into the cylinder chamber without restriction through the port 58 moving the piston to the other end of the cylinder, from which the fluid is released through check valve 21 and the restriction at 22 to the conduit 15 and from there to the return conduit 38 via the conduit 27 and the passages in the control valve. By proper adjustment of the restrictions at 19, 22, 23 and 26, the desired accelerations and speeds of operation of the piston 43 may be obtained in moving the cradle at the desired speeds under the prevailing loads. The novel arrangement consisting of the two check valves and the two adjustable orifices at each end of the cylinder is provided in order to take care of the unbalanced and continuously varying loads imposed upon the cradle operating cylinder during the movement of the cradle. The direction and magnitude of the loads imposed upon the cradle operating cylinder during the movement of the cradle may be considered as divided into three phases:

1. Starting with the cradle in its fully retracted position and moving the cradle towards its extended position, there exists a region in which the unbalanced weight of the cradle will tend to return the cradle to its fully retracted or upright position.

2. A comparatively small region in which the cradle is balanced and no load is imposed upon the cradle operating cylinder.

3. A region in which the unbalanced weight of the cradle will tend to move the cradle to its fully extended position.

The operation of the hydraulic system is as follows: Referring to the diagrammatic illustrations of Figs. 6 and 7, when the control valve is shifted to the position shown in Fig. 6, fluid under pressure from the pump will be ported through the control valve to the head end of the operating cylinder, and the piston rod end of the cylinder will be vented to the tank. At the head end of the hydraulic cylinder the oil will be blocked by check valve 21 but will be ported through the check valve 20 then through the orifice 19 to the left side of the piston. The force on the piston will cause the piston to move to the right, thereby rotating the cradle. The discharge from the piston rod side of the operating cylinder will be ported through the upper check valve 24 and through the adjustable orifice 23 to the tank. The pressure drop across each orifice will limit the force applied to the piston rod and thus control the acceleration of the cradle.

During the first part of the piston movement the flow of oil will pass into the two orifices 19 and 23. However, as soon as the piston uncovers a port 57 in the cylinder the oil will flow directly into the cylinder without passing through the orifice 19 at the upper left side. By proper adjustment of the orifice 19 at the upper left side of the operating cylinder, the desired acceleration of the cradle may be obtained.

During the last part of the cradle movement, the unbalanced weight of the moving system tends to move the cradle to its fully extended

position. However, the maximum speed of the piston will be limited by the pressure drop across the orifice 23 at the upper right side of the operating cylinder. The final deceleration and stopping of the cradle is accomplished by an external buffer 50. Thus, it can be seen that one orifice 19 controls the acceleration of the cradle and the second orifice 23 controls the maximum speed of the cradle, thus reducing and limiting the shock on the moving system. The operation of rotating the cradle from its extended to its retracted position is shown in the diagram of Fig. 7. The action is similar to that described above, except that the second pair of check valves 25 and 21 and adjustable orifices 26 and 22 shown at the bottom of the cylinder will be used instead of the upper pair of valves 20 and 24 and orifices 19 and 23.

The sectional view of the swivel joint in Fig. 3 shows the two main conduits 27 and 28 from the control valve and the two main conduits 15 and 16 leading to the oscillatable cradle operating cylinder. A third conduit 18 of a smaller diameter is also shown with two connections to each end of the operating cylinder. The purpose of this conduit is to drain to the tank the oil leakage past the piston rod packing and all the adjustable orifice rods. Tank connections 51, 52 and 53 are also shown for the oil seepage past the swivel joints of the fittings 55 and 56.

The connections of the conduit 18 to the several points of oil leakage may be more clearly seen in Figs. 8 to 10, wherein 53' is the interconnecting conduit in the wall at the head end of the cylinder between the two orifice rods at that end. A similar conduit in the wall at the piston rod end of the cylinder may be seen interconnected with the leakage chamber from the packing around the piston rod 14.

This invention is not limited to the preferred forms of the details of the device herein disclosed, but may be varied within the scope of the appended claims.

The invention described herein may be manufactured and used by or for the Government of the United States of America for governmental purposes without the payment of any royalties thereon or therefor.

What is claimed is:

1. A cradle operating mechanism comprising a base support, a cylinder pivotally connected at one end to said support and having a hydraulically actuated piston therein with a piston rod extending through the other end and pivoted to the cradle, a port in the cylinder wall near each end of the cylinder closed by the piston when at the corresponding end, two check valves and two restrictions at each end of the cylinder, and a fluid supply and relief conduit for each end of the cylinder connected for supplying fluid through one of the check valves to said port, and to the extreme end of the cylinder by way of one of the restrictions, and for relieving fluid from said end by way of the other check valve and the other restriction.

2. A cradle operating mechanism comprising a base support, a cylinder pivotally connected at one end to said support and having a hydraulically actuated piston therein with a piston rod extending through the other end and pivoted to the cradle, a port in the cylinder wall near each end of the cylinder closed by the piston when at the corresponding end, two check valves and two restrictions at each end of the cylinder, a fluid supply and relief conduit for each end of the cylinder

der connected for supplying fluid through one of the check valves to said port, and to the extreme end of the cylinder by way of one of the restrictions, and for relieving fluid from said end by way of the other check valve and the other restriction, and a control valve for selectively admitting fluid under pressure to either one of said fluid supply and relief conduits while relieving the other.

3. A cradle operating mechanism comprising a base support, a cylinder pivotally connected at one end to said support and having a hydraulically actuated piston therein with a piston rod extending through the other end and pivoted to the cradle, a port in the cylinder wall near each end of the cylinder closed by the piston when at the corresponding end, two check valves and two restrictions at each end of the cylinder, a fluid supply and relief conduit for each end of the cylinder connected for supplying fluid through one of the check valves to said port, and to the extreme end of the cylinder by way of one of the restrictions, and for relieving fluid from said end by way of the other check valve and the other restriction, and means for adjusting the size of each of the restrictions to regulate the speed of operation of the piston.

4. A cradle operating mechanism comprising a base support, a cylinder pivotally connected at one end to said support and having a hydraulically actuated piston therein with a piston rod extending through the other end and pivoted to the cradle, a port in the cylinder wall near each end of the cylinder closed by the piston when at the corresponding end, two check valves and two restrictions at each end of the cylinder, a fluid supply and relief conduit for each end of the cylinder connected for supplying fluid through one of the check valves to said port, and to the extreme end of the cylinder by way of one of the restrictions, and for relieving fluid from said end by way of the other check valve and the other restriction, and swivelled fittings on the axis of the cylinder pivot in the base support, connected to the fluid supply and relief conduits for turning with the cylinder, and through the swivelled joints to passages in the base structure having fittings for connection to stationary portions of the fluid supply and relief conduits.

5. A cradle operating mechanism comprising a base support, a cylinder pivotally connected at one end to said support and having a hydraulically actuated piston therein with a piston rod extending through the other end and pivoted to the cradle, a port in the cylinder wall near each end of the cylinder closed by the piston when at the corresponding end, two check valves and two restrictions at each end of the cylinder, a fluid supply and relief conduit for each end of the cylinder connected for supplying fluid through one of the check valves to said port and to the extreme end of the cylinder by way of one of the restrictions and for relieving fluid from said end by way of the other check valve and the other restriction, and swivelled fittings on the axis of the cylinder pivot in the base support connected to the fluid supply and relief conduits for turning with the cylinder, and through the swivelled joints to passages in the base structure having fittings for connection to stationary portions of the fluid supply and relief conduits.

6. A cradle operating mechanism comprising a base support, a cylinder pivotally connected at one end to said support and having a hydraulically actuated piston therein with a piston rod

extending through the other end and pivoted to the cradle, a port in the cylinder wall near each end of the cylinder closed by the piston when at the corresponding end, two check valves and two restrictions at each end of the cylinder, a fluid supply and relief conduit for each end of the cylinder connected for supplying fluid through one of the check valves to said port and to the extreme end of the cylinder by way of one of the restrictions, for relieving fluid from said end by way of the other check valve and the other restriction, and swivelled fittings on the axis of the cylinder pivot in the base support connected to the fluid supply and relief conduits for turning with the cylinder and through the swivelled joints to passages in the base structure having fittings for connection to stationary portions of the fluid supply and relief conduits and a control valve for selectively admitting fluid under pressure to either one of said fluid supply and relief conduits while relieving the other.

7. A cradle operating mechanism comprising a base support, a cylinder pivotally connected at one end to said support and having a hydraulically actuated piston therein with a piston rod extending through the other end and pivoted to the cradle, a port in the cylinder wall near each end of the cylinder closed by the piston when at the corresponding end, two check valves and two restrictions at each end of the cylinder, a fluid supply and relief conduit for each end of the cylinder connected for supplying fluid through one of the check valves to said port and to the extreme end of the cylinder by way of one of the restrictions, and for relieving fluid from said end by way of the other check valve and the other restriction, swivelled fittings on the axis of the cylinder pivot in the base support connected to the fluid supply and relief conduits for turning with the cylinder, and through the swivelled joints to passages in the base structure having fittings for connection to stationary portions of the fluid supply and relief conduits, and means for adjusting the size of each of the restrictions to regulate the speed of operation of the piston.

8. A cradle operating mechanism comprising a base support, a cylinder pivotally connected at one end to said support and having a hydraulically actuated piston therein with a piston rod extending through the other end and pivoted to the cradle, a port in the cylinder wall near each end of the cylinder closed by the piston when at the corresponding end, two check valves and two restrictions at each end of the cylinder, a fluid supply and relief conduit for each end of the cylinder connected for supplying fluid through one of the check valves to said port and to the extreme end of the cylinder by way of one of the restrictions, and for relieving fluid from said end by way of the other check valve and the other restriction, and swivelled fittings on the axis of the cylinder pivot in the base support connected to the fluid supply and relief conduits for turning with the cylinder, and through the swivelled joints to passages in the base structure having fittings for connection to stationary portions of the fluid supply and relief conduits, a control valve for selectively admitting fluid under pressure to either one of said fluid supply and relief conduits while relieving the other, and means for adjusting the size of each of the restrictions to regulate the speed of operation of the piston.

9. Hydraulic means for reciprocating a piston in either direction for producing a desired cycle of varying forces during the piston stroke, a cyl-

inder for said piston, a source of fluid under constant pressure, a supply and relief conduit for each end of the cylinder, a pair of valves and a pair of adjustable orifices for each end of the cylinder, a connection from each conduit to the extreme end of the cylinder through one of the pair of check valves and one of the pair of adjustable orifices, another connection from said end to said conduit through the other of the check valves and the other of the adjustable orifices, a port near the end of the cylinder closed by the piston when at the extreme end of the cylinder and connected between said first check valve and said first orifice.

10. Hydraulic means for reciprocating a piston in either direction for producing a desired cycle of varying forces during the piston stroke, a cyl-

inder for said piston, a source of fluid under constant pressure, a supply and relief conduit for each end of the cylinder, a pair of valves and a pair of adjustable orifices for each end of the cylinder, a connection from each conduit to the extreme end of the cylinder through one of the pair of check valves and one of the pair of adjustable orifices, another connection from said end to said conduit through the other of the check valves and the other of the adjustable orifices, a port near the end of the cylinder closed by the piston when at the extreme end of the cylinder and connected between said first check valve and said first orifice, and means for adjusting the size of each of said orifices.

DAVID WERTMAN.
FRANK WARLICK.
